UNITED STATES PATENT OFFICE

JAMES S. BACK, OF OTTAWA, CANADA.

DESIGN FOR A GUITAR-BODY.

SPECIFICATION forming part of Design No. 27,561, dated August 24, 1897.

Application filed February 18, 1897. Serial No. 624,058. Term of patent 14 years.

To all whom it may concern:

- Be it known that I, JAMES S. BACK, a subject of the Queen of Great Britain, residing in Ottawa, in the Province of Ontario and Dominion of Canada, have invented and produced a new and original Design for a Guitar-Body, of which the following is a specification, reference being made to the accompanying drawings, forming a part thereof.
- 10 Figure 1 of the drawings shows a perspective view of my new and original design for a guitar-body; Fig. 2, a longitudinal section on line $x x$ of Fig. 1; and Fig. 3, a cross-section on line $y y$, Fig. 1.
  - 15 The leading feature of my design consists in a longitudinal central swell in the top of the instrument and a bar having a correspondingly-curved base mounted on it.
  - 20 a represents the top of the instrument, having a large circular hole a' and a longitudinal central swell a^2 .

b represents the rim, and c the neck, having a head d .

e represents a bar having its base curved to correspond to the central swell of the top, said 25 bar being mounted on and fitted to the top and placed crosswise at a point substantially midway between the hole a' and the lower end of the top.

I claim—

The design for a guitar-body as herein shown and described.

In testimony whereof I have signed my name to this specification in the presence of two subscribing witnesses.

JAS. S. BACK.
